UNITED STATES PATENT OFFICE

139,042

DESIGN FOR A CONVEYER

Walter W. Pabst, Elizabeth, N. J.

Application November 18, 1943, Serial No. 111,724

Term of patent 14 years

(Cl. D55—1)

To all whom it may concern:

Be it known that I, Walter W. Pabst, a citizen of the United States, residing at the city of Elizabeth, in the county of Union, and State of New Jersey, have invented a new, original, and ornamental Design for a Conveyer, of which the following is a specification, reference being had to the accompanying drawing, forming part thereof.

The figure is a perspective view of a conveyer showing my new design.

The other side of the conveyer, not shown, is substantially like the side shown.

I claim:

The ornamental design for a conveyer, as shown and described.

WALTER W. PABST.
